LIGHT REFLECTOR AND SHIELD COMBINATION
 John R. Watson, 2517 Carlisle, Dallas, Tex.
 Filed Sept. 20, 1963, Ser. No. 310,225
 3 Claims. (Cl. 240—3.1)

This invention has to do with a light reflector and shield assembly, and is particularly concerned with a novel adjustable light shield and means for detachably mounting therein circular lenses.

In landscape lighting, light fixtures, including reflectors and shields with colored lenses therein, are mounted on trees, hedges, walls or posts in position so that light will be directed and reflected in desired directions in such a way that the light will be diffused over the landscape, but no fixtures or direct light sources are viewable.

In the practice of such art, it is desirable to have a fixture with a shield and reflector thereon which may be quickly adjusted to reflect and direct light in the desired direction at the time of, or after installation, and to support the colored lenses therein in such manner that they may be quickly and easily removed for changing or to allow the incandescent bulb in the fixture to be changed or cleaned.

It is the primary object of this invention to supply a light fixture and shield combination with means for mounting the lens therein which will answer the requirements set forth above.

It is another object of the invention to provide a light fixture and shield combination wherein the shield may be rotatably adjusted with relation to the bulb mounting fixture to direct light in the desired direction, and wherein the colored lenses are detachably mounted therein in such a manner that they may be easily and quickly changed.

Still another object of the invention is to provide a combination light fixture and shield, with lenses detachably mounted therein, in which the shield and lens unit is a self-contained unit attached to the fixture in adjusted relationship thereto.

Still another object of the invention is to provide a shield and lens combination wherein the shield may be adjustably mounted to a light fixture wherein the shield is in the shape of an ungula of a right angular cylinder having a split base attachable about the outer end of a light fixture so that the shield may be adjustably directed in a desired direction, to reflect and direct diffused light in any desired direction.

Other and further objects of the invention will become apparent upon reading the detailed specification herein-after following, and by referring to the drawing annexed hereto.

A suitable embodiment of the invention is shown in the attached drawing wherein:

FIGURE I is a top perspective view of the combination light fixture and shade assembly;

FIGURE II is a cross-sectional, elevational view taken on the line II—II of FIGURE III;

FIGURE III is a front end elevational view of the combination light fixture and shield;

FIGURE IV is a fragmentary, transverse cross-sectional view taken on the line IV—IV of FIGURE II; and

FIGURE V is a fragmentary, cross-sectional elevational view taken on the line V—V of FIGURE IV.

Numerical references are employed to indicate the various parts shown in the drawing, and like numerals indicate like parts throughout the various figures of the drawing.

The numeral 1 indicates a light fixture housing which is hollow and open at its outer end.

An electrical socket 2 is mounted in the housing 1 and is secured thereto by means of a bracket 3 and a screw 3a extending through the rear end of the housing.

A floodlight bulb 4 is screwed into the socket 2 and

2

power is supplied to the floodlight 4 through the electric leads 4a extending through a cable 4b to a suitable source of power.

The housing 1 is attached to a mounting bracket 5 through a rotatable and adjustable joint 6. The mounting bracket 5 has an enlarged base 7 as a part thereof which is secured to a mounting plate 8 by means of screws 10. The mounting plate 8 may be secured to a tree, post, wall, or other desired support by means of nails 9, which may be masonry nails, as shown.

A shield 11 is detachably and adjustably secured to the outer open end of the fixture housing 1.

The shield 11 is hollow and when mounted to the housing 1 is in the shape of an ungula of a right angular cylinder, which includes a semi-elliptical shaped outer edge 12 providing a laterally directed opening 12a, and has a circular base 13 which is split as indicated at 14, so that it may be placed about the outer end of the housing 1 and grippingly engaged thereto by an expandable and contractible joint consisting of the nut and bolt assembly 17, which passes through aligned holes in the brackets 15 and 16, secured to opposite edges of the base 13, and drawn together by means of the nut 17a threaded upon the outer end of the bolt 17.

Thus the shield 11 is detachably secured to the outer end of the housing 1 and is attached in such a way that it may be rotated about the outer end of the housing by simply loosening the nut 17a, and then securing same in adjusted position by tightening the nut 17a. Thus the direction of the opening 12a of the shield 11 may be adjusted at the time of, and after installation of, the fixture to direct the light in the desired direction.

Disc-like light lens assembly 18, as shown, is comprised of two lenses 19, which are transparent and usually colored, and are supported by a metallic rim 20.

The lenses 19 are detachably supported in the base 13 of the shield 11 in such a manner that they may be quickly and easily removed and changed, and are assembled in such a way that the lens and shield combination is an integral unit so that a complete shade and lens assembly may be substituted on a given fixture, to change the color of light emitted therefrom by simply loosening the nut 17a, removing the shield and lens combination, and substituting another therefor having the desired color of lens therein. In such manner the color of the light in the landscaped area may be quickly changed.

For instance, it may be desired to have a moonlight effect and blue shades would be employed, and on another occasion it might be desired to have amber shades to give a twilight effect, and on still other occasions it might be decided that a daylight effect be given by having clear lenses in the shade.

The lens assembly 18 is detachably mounted in the shield 11 by means of threaded screws 21, which extend through appropriate spaced holes in the shield 11 provided through the wall of the base portion 13 of the shield 11, which have wing-like brackets or lugs 23 threaded on the inner ends thereof having outwardly extending wings 24 thereon providing aligned channels 25 arranged to receive the rim 20 of the lens assembly 18. There should be at least three of said brackets 23, which should preferably be spaced approximately 120° apart. The lens assembly 18 is thus detachably held in place by the annularly spaced wing brackets 23, and may be quickly and easily removed for mounting of outer lens assembly having lenses therein of a different color if desired, by simply unscrewing screw 17 from nut 17a sufficiently to allow the edges of the split base 14 to spread apart sufficiently to permit the lens assembly to be withdrawn from channels 25. The lens assembly may be easily replaced and gripped in the channels 25 by simply reversing this procedure. It will be

observed that the lens assembly is mounted in the shield base 13 in such a manner that the lenses are spaced from the bulb 4 so that no direct heat is imparted thereto.

Appropriate spacer nuts 26 are provided for adjusting the relationship of the wing brackets 23 with relation to the rim of the lens.

It will thus be seen that I have provided a combination light fixture, shield and shade assembly which is quickly adjustable to allow light to be directed in the desired direction, wherein the lens may be quickly and easily changed and wherein the shield and lens assembly attachable to the housing of the light fixture is a separate and unitary assembly which may be attached as a unit to the light fixture housing, and which provides a combination which is uniquely adapted for use in landscape lighting wherein diffused light may be directed in desired directions without exposing the source of light to view and wherein the light lens may be quickly changed if desired without disassembling the unit or without the necessity of de-mounting the entire light fixture.

It will be understood that other and further forms of the invention may be devised without departing from the spirit and scope of the appended claims.

Having described my invention, I claim:

1. In a device of the class described,
a housing

having an opening in the outer end thereof;
a hollow shield in the shape of an ungula of a cylinder;
the base of the shield being divided to provide
separable edges
and being positionable about the open outer end
of the housing;
expansible and contractible joinder means to draw
the separable edges together to cause the base
to grippingly engage the housing;

10
15
20
25
30

35

4
a plurality of aligned brackets spacedly mounted about
the inner side of the base;

each said bracket having a pair of oppositely dis-
posed wings thereon to provide aligned channels
on the outer sides thereof;

and a lens assembly

having a rim thereabout positionable in the aligned
channels in the brackets.

2. The combination called for in claim 1 with the addition of

a light bulb in the housing,
the said brackets being so spaced with relation to the
outer end of the bulb

that the lens is spaced from the outer end of the
bulb when the rim of the lens is engaged in the
channels.

3. The combination called for in claim 1 wherein
the brackets are threadedly attached to screws extending
through the wall of the base

whereby they may be adjusted inwardly or out-
wardly with relation to the rim of the lens.
